(57) **CLAIM**

What is claimed is the ornamental design for landscape edging, as shown and described.

DESCRIPTION

FIG. 1 is a front perspective view of a landscape edging showing our new design;

FIG. 2 is a rear perspective view thereof;

FIG. 3 is a front view thereof;

FIG. 4 is a right side view thereof;

FIG. 5 is a top view thereof;

FIG. 6 is a rear view thereof;

FIG. 7 is a left side view thereof; and,

FIG. 8 is a bottom view thereof.

The broken lines in the drawings represent portions of the landscape edging that form no part of the claimed design.
